(57) **CLAIM**

The ornamental design for stethoscope tubing, as shown and described.

DESCRIPTION

FIG. 1 is a front view of stethoscope tubing showing our new design;

FIG. 2 is a right side view thereof;

FIG. 3 is a left side view thereof;

FIG. 4 is a top view thereof;

FIG. 5 is a bottom view thereof; and,

FIG. 6 is a rear view thereof.

The broken lines are directed to environment and are for illustrative purposes only; the broken lines form no part of the claimed design.

FIGS. 2-5 are shown separate from the environment to show aspects of the design that are not apparent in the other views.

1 Claim, 3 Drawing Sheets

FIG. 1

FIG. 2   *FIG. 3*

FIG. 4

FIG. 5

FIG. 6
